CUFF LINK OR CUFF BUTTON

Carl I. Osterberg, Providence, R. I., assignor to
Arthur J. Schwartz, New York, N. Y.

Application April 20, 1948, Serial No. 22,187

11 Claims. (Cl. 24—97)

1

This invention relates to cuff-links or cuff-buttons and consists in improvements in the construction and method of operation of the same. The invention is particularly directed to a cuff-link or button having one or both of its heads swiveled to rock into alignment with the shank connecting the heads to adapt it for convenient insertion through or withdrawal from the buttonholes of the cuff.

One object of the invention is to provide a cuff-link of the type indicated having a rockable head with means for positively locking it in perpendicular or right-angular relation to the shank of the cuff-link, said locking means being manually-operable for releasing the head to permit it to rock into alignment with the shank.

Another object is to provide positive locking means for the head of the cuff-link which can only be released by manual sliding movement of the locking means in a direction perpendicular to the shank on which the head is pivotally mounted.

Another object is to provide a cuff-link of the type indicated in which the locking means for the head may be operated manually by pressing it in either direction crosswise or laterally of the shank on which the head is pivoted.

Another object is to provide a cuff-link of the type indicated in which the positive locking means is normally held against releasing movement by resilient means such as a spring or springs contained within the head.

Another object is to provide a cuff-link having a pivoted head or heads with the positive locking means therefor of simple construction, not subject to wear or derangement and durable for long periods of use.

Further objects of the invention are set forth in the following specification which describes a preferred form of construction of the present improved cuff-link as illustrated by the accompanying drawing. In the drawing:

Fig. 1 is an enlarged side view of the improved cuff-link shown as comprising a relatively stationary or rigid head at one end of its shank and a pivotally-mounted head at the opposite end thereof adapted to be rocked into alignment with said shank;

Fig. 2 is another side view of the cuff-link looking in the direction indicated by the arrow in Fig. 1;

Fig. 3 is a greatly enlarged fragmentary view of a portion of the bifurcated shank of the cuff-link showing the construction of the pivoting

means for the head in section on line 3—3 of Fig. 4;

Fig. 4 is a greatly enlarged side view of the rockable head of the cuff-link showing one arm or leg of the bifurcated shank as broken away to illustrate the pivotal mounting for the head;

Fig. 5 is a similar part-sectional view showing the sliding locking element for the rockable head which is manually operable to release the locking means;

Fig. 6 is a longitudinal sectional view of the head taken in a median vertical plane and showing the head locked in crosswise or perpendicular relation to the shank of the button;

Fig. 7 is a similar view showing the manually-operable locking element as slid to release the head and permit it to rock;

Fig. 8 is a similar view showing the head as unlocked and partially turned toward alignment with the shank of the cuff-link or button;

Fig. 9 is a similar view showing the head unlocked and turned completely into alignment with the shank of the cuff-link or button; and

Fig. 10 is a sectional plan view of a portion of the head showing the spring-pressed plungers within the locking element as engaging against the ends of the inturned flanges at the sides of its central slot which restricts their motion under pressure of the springs and prevents them from engaging against the sides of the pivot-pin.

Heretofore in the present art various forms of cuff-links having rockable heads have been proposed and patented, but in most of these the head is maintained in crosswise relation to the shank of the cuff-link or button under spring pressure; the head being rockable against tension of the springs which maintain it locked. That is to say, usually the heads are pivoted on

pins or crossbars of polygonal or rectangular cross-section with springs pressing against the flat sides of the pin to normally prevent the head from rocking about the pivot. With such a form of construction when the springs are

relatively strong, considerable resistance is encountered to the rocking movement of the head; whereas, when the springs are relatively weak, as they must be to provide for convenient manipulation of the head, the head becomes loose and shakily at its joint and the locking means therefor is less efficient. In the latter case the head may be rocked accidentally to cause release of the cuff-link from the cuff and sometimes loss thereof.

It is therefore an important object of the

present invention to provide a cuff-link or cuff-button in which the head or crossbar at the end of the shank is locked positively against turning or rotating about its pivot unless or until the locking means is released by manual operation. Stated another way, in the present improved construction the rockable head of the cuff-link is held positively and rigidly against pivoting until the manually-operable locking element is pressed by the fingers to release the lock. One advantage of this form of construction is that it insures against the pivotally-mounted head on the cuff-link being rocked or turned on its pivot accidentally through contact with another object; and further, it eliminates loose and shacky joints between the rockable head and its mounting on the shank of the cuff-link. With these objects and advantages in view the present improved cuff-link is preferably constructed as next described and illustrated in the accompanying drawing.

Fig. 1 of the drawing is a side view of a cuff-link or button embodying the present invention and comprising a fixed or rigid head 2 shaped, for example, like a crowned button with a bifurcated shank 3 projecting from its center. The shank 3 may comprise two arms or legs 4 and 5 struck up from sheet-metal in strip form and folded or bent to provide a cross-member 6 which is soldered or otherwise attached to the back of the button-like head 2. The legs 4 and 5 of the shank may be of ornamental contour with outwardly-curved marginal edges and circular portions 7 at their upper ends. The legs 4 and 5 may be of convex form on their outer faces throughout a portion of their length and flattened on the sides at 8 towards their circular ends 7.

The rockable head 10 of the cuff-link may take different forms, being herein shown as of tubular construction and rectangular in cross-section, see Figs. 2 and 3. In other instances, however, the rockable head 10 may be part cylindrical or circular in cross-section and of ovate shape as viewed from the side. As herein illustrated the head 10 is in the form of a flat-sided hollow bar within which a close-fitting tubular locking element 12 of similar shape is slidably mounted. Referring to Fig. 4, the head 10 is provided with circular openings 11 on its opposite sides for receiving a transverse pivot-pin 15 which extends between the opposite legs 4 and 5 of the bifurcated shank 3. The pivot-pin 15 may be fixedly secured in square holes in the legs 4 and 5 of the shank 3 by soldering, riveting or any other suitable means.

The inner tubular locking element 12 is slideable longitudinally within the head 10 and provides the means for rigidly holding the cross-member or head 10 in either one of two positions; that is, extending at right-angles or perpendicular to the shank 3, or disposed in alinement therewith when it is rocked in either direction to carry one of its ends downwardly between the opposite legs of the shank.

As has been stated, the inner slideable locking member 12 is closely fitted within the four sides of the head 10 but adapted to be manually slid longitudinally thereof by pressure on either of its ends. For this purpose the ends of the slideable locking element 12 normally project equal distances beyond the ends of the head 10 as shown in Figs. 1, 4, 5 and 6. The flat sides of the locking element 12 are punched or otherwise formed with circular openings 16 and 17 spaced at a distance apart and joined by straight-sided passages or slots 18 bounded by flanges 19 and 20

projecting inwardly from the sides thereof. That is to say, the metal between the circular openings 16 and 17 is sheared or split and then bent inwardly at top and bottom to form the flanges 19 and 20 which are contiguous with the edges of the slots 18. By this form of construction the flanges 19 and 20 provide extended bearing faces adapted to engage the flat faces of the pivot-pin 15 when the slideable locking element 12 is centralized longitudinally of the outer member or head 10, see Fig. 5.

The flanges 19 and 20 also have another particular purpose; that is, to form stops or detents for a pair of block-like plugs or plungers 24 and 25 which are mounted to slide within the inner tubular locking member 12 on opposite sides of the pivot-pin 15. As shown in Fig. 6, the plungers 24 and 25 are urged toward each other by helical springs 26 and 27 held under compression within the locking element 12 by means of closure caps 28 and 29 soldered or otherwise secured within the ends of said element. As shown more clearly in Figs. 8 and 10, the flanges 19 and 20 may be formed from the metal cut from the sides of the locking element 12 to provide the slots 18, being bent at right-angles thereto to partially bridge the space therebetween. The flanges 19 and 20 thus provide for extended contact with the flat sides of the pivot-pin 15 to secure a firm, positive locking engagement therewith while reducing wear and increasing the durability of the parts.

It has been explained that the pressure of the springs 26 and 27 exerted against the slideable plunger-plugs 24 and 25 causes them to abut against the ends of the flanges 19 and 20, a slight space or clearance being left between the inner face of each plug and the lateral side of the pivot-pin 15. In other words, the plunger-plugs are not caused to bear against the sides of the pivot-pin 15 for functioning to hold the head 10 in its normal position disposed at right-angles or perpendicular to the shank 3. Stated more specifically, it is the engagement of the flat faces of the flanges 19 and 20 with the flat sides of the pivot-pin 15 which constitutes the locking means for holding the head 10 from turning on the pivot-pin when the head is either in its normal position as shown in Fig. 6 or rocked into alinement with the shank 3. In this way, a rigid positive lock for the head 10 is provided by the extended bearing engagement between the flanges 19 and 20 and the square sides of the pivot-pin 15 to guard against wear and a loose or shacky joint between the head and the shank 3.

To permit rotation or rocking of the head 10 on the pivot-pin 15 the inner locking element 12 must be slid one way or the other by pressure on its end. By simply pressing the finger against either end of the locking member 12 it may be slid longitudinally within the head 10; for example, in the manner shown in Fig. 7, thereby compressing the spring 26. By this manual operation the locking element 12 is shifted in position to withdraw the flanges 19 and 20 on its sides from engagement with the flat sides of the pivot-pin 15 while causing the pin to enter the circular openings 16 in the sides of the locking element. Thereafter, the head 10 may be rotated about the pivot-pin 15 as shown in Fig. 9 to carry one end down between the legs 4 and 5 of the shank 3 into alinement with the latter. As soon as the head 10 has been turned into alinement with the shank 3 of the cuff-link, in the manner last explained, pressure on the end of the lock-

ing element 12 is released and the spring 26, which has been tensioned under the pressure, will expand to cause the locking element to slide back into centralized relationship within the head. Under this action the flanges 19 and 20 will engage against the lateral flat faces of the pivot-pin 15 to positively lock the head in alignment with the shank 3. It thus will be observed that in whichever position the head 10 is adjusted it will be locked positively instead of by the pressure of the springs so that accidental turning movement of the head is prevented. Stated another way, the spring-pressed plunger-plugs 24 and 25 have no function to hold the head in locked position on the shank 3 of the cuff-link, their only purpose being to resist the sliding movement of the locking element 12 or to return said element into locking engagement with the pivot-pin 15.

After the head 10 and shank 3 of the cuff-link have been inserted through the button-holes in the sides of the cuff it is only necessary to again press on one end of the locking member 12 to release the flanges 19 and 20 from engagement with the flat sides of the pivot-pin 15 to allow the head to be turned cross-wise of the shank and positively locked in this relationship for holding the sides of the cuff in connection. This operation of releasing the locking means and turning the head crosswise of the shank of the cuff-link may be accomplished by one motion of the finger; that is, by simply pressing against one end of the locking element and at the same time carrying the fingers toward the fixed head 2 to turn the head on its pivot.

It will be observed from the foregoing description and by reference to the accompanying drawing that the present invention provides an extremely simple yet efficient cuff-link or cuff-button which is convenient to adjust for inserting it through and withdrawing it from the button-holes of a cuff. It has been explained that the rockable head of the cuff-link is locked in either one of its two positions by positively-acting means without dependence upon spring pressure against the locking means for holding it engaged. That is to say, the flat sides of the pivot-pin are engaged positively by the flanges 19 and 20 at the edges of the slots 18 in the locking element 12 and the engaging faces are extended to provide a firm, rigid lock for the head 10. Consequently, insurance against wear is attained and loose, shakily joints in the pivotal connection between the head and the shank of the cuff-link prevented, while guarding against accidental turning of the head. The springs in the head are employed solely for locating the locking element centrally of the head with the flanges bordering its slots in locking engagement with the sides of the pivot-pin without functioning to apply pressure to the locking means. Even though the locking element may be displaced slightly by striking against another object it will not release the lock, a very considerable movement of the locking element being necessary to accomplish this purpose. The present improved locking means is therefore much more dependable in action and less liable to derangement or getting out of order than previous devices heretofore used, besides providing for most convenient manipulation of the head of the cuff-link in applying it to use.

While the invention is herein shown as embodied in a preferred form of construction, it is to be understood that variations may be made

in the structure and arrangement of the parts of the device without departing from the scope of the appended claims. Therefore, without limiting myself in this respect, I claim:

- 5 1. A cuff-link or button having a shank, a pivot-pin on the shank formed with flat faces on its sides, a rockable head pivoted on the pin, and a locking element slidably mounted on the head and formed with a slot engageable with the flat sides of the pivot-pin to prevent the head from rocking, said locking element having a substantially circular opening communicating with its slot and adapted to be carried into register with said pivot-pin by sliding said element to permit the head to be rocked.
- 10 15 2. A cuff-link or button having a shank, a rockable head, a pivot-pin for rockably mounting the head on the shank, said pivot-pin having flat faces on its sides, and a locking element slidably mounted relatively to the head and formed with a slot engageable with the flat sides of the pivot-pin to prevent the head from rocking on the shank, said locking element having a substantially circular opening communicating with the end of its slot and adapted to be carried into register with said pivot-pin when said element is slid to disengage its slot from the flat sides of the pin whereby the head may be rocked on the shank.
- 20 25 30 35 40 3. A cuff-link or button having a bifurcated shank, a pivot-pin extending between the bifurcations of the shank and formed with flat faces on its sides, a rockable head having a circular opening for pivotally mounting said head on the pivot-pin, and a locking element slidably relatively of the head and formed with a slot engageable with the flat sides of the pivot-pin to restrain the head from rocking thereon, said locking element having a circular opening communicating with its slot and shiftable into register with the pivot-pin by sliding the element to permit the head to rock on the shank.
- 45 4. A cuff-link or button provided with a bifurcated shank, a pivot-pin of rectangular cross-section extending between the bifurcations of the shank and secured thereto at its ends, a head having a circular opening surrounding the pivot-pin to adapt the head to rock thereon, a locking element slidably longitudinally of the head and formed with a slot engageable with the flat sides of the pivot-pin to restrain the head from rocking thereon, said locking element having a circular opening communicating with its slot and shiftable into position enclosing the pivot-pin by sliding the element to permit the head to rock on the pin, and resilient means for normally maintaining said locking element in position with its slot engaging the flat sides of the pivot-pin.
- 50 55 60 65 5. A cuff-link comprising a relatively fixed head having a bifurcated shank projecting therefrom, a pivot-pin of polygonal cross-section having flat faces on its sides, said pin extending between the bifurcations of the shank with its ends fixedly secured thereto, a head of tubular form having circular openings in its sides for rockably mounting it on the pivot-pin, a manually-operable locking element slidable in the head and formed with a central straight-sided slot engageable with the opposite flat sides of the pivot-pin to lock the head from turning on the pin, said slidable locking element having a circular opening at the end of its slot for receiving the pivot-pin to adapt the head to rock on the pin, and resilient means for normally maintaining said slidable element in

position with its slot engaging the flat sides of the pivot-pin.

6. A cuff-link comprising a bifurcated shank, a pivot-pin of polygonal cross-section extending between the bifurcations of the shank with its ends secured thereto, a movable head of hollow construction provided with circular openings in its sides for mounting it to rock on the pin, a manually-operable locking element slideable longitudinally within the hollow head and formed with a longitudinal slot engageable with the opposite flat sides of the pivot-pin to hold the head from rocking, said locking element having a pair of circular openings communicating with the ends of the slot to adapt one or the other to be shifted into register with the pivot-pin by sliding said element whereby to permit the head to rock about the pin, and resilient means for normally maintaining said locking element in mid position with its slot engaged with the flat faces of the pivot-pin to prevent rocking of the head about the pin.

7. A cuff-link or button of the type indicated comprising a bifurcated shank, a pivot-pin of rectangular cross-section extending between the bifurcations of the shank, a head mounted on the pin to rock about the axis thereof, a locking element slideable longitudinally of the rockable head and provided with a slot for engagement with the flat sides of the pivot-pin to lock said head from rocking, said locking element having a circular opening communicating with its slot and adapted to be shifted into position enclosing the pivot-pin when the locking element is slid on the head whereby to permit the head to rock, and means for normally maintaining the locking element in position with the sides of its slot engaging the flat sides of the pivot-pin.

8. A cuff-link or button comprising a bifurcated shank, a pivot-pin of rectangular cross-section extending between the bifurcations of the shank, a tubular head of rectangular cross-section having circular openings in its sides enclosing the pivot-pin to adapt the head to rock on the pin, a locking element slideable within the head and provided with a slot engageable with the flat sides of the pivot-pin to lock the head from rocking thereon, said locking element having a circular opening shiftable into a position enclosing the pivot-pin to release the locking engagement of the slot therewith and permit the head to rock, a spring in said locking element, and a plunger slideable in the element under the tension of the spring to normally maintain the locking element with its slot engaging the flat sides of the pin to lock the head from rocking.

9. A cuff-link or button of the type indicated having a bifurcated shank, a pivot-pin of rectangular cross-section extending between the bifurcations of the shank, a tubular head of rec-

tangular cross-section having circular openings in its sides for mounting it on the pin to adapt it to rock into alignment with the shank, a tubular locking element of rectangular cross-section slideable in the tubular head and having a central slot with flanges on its sides engageable with the flat sides of the pivot-pin to restrain the head from rocking thereon, said locking element having circular openings communicating with the ends of its slot to adapt one or the other of said openings to be shifted into position to permit the head to rock on the pivot-pin, and springs for normally maintaining the locking element in position with the flanges on the sides of its slot engaging the sides of the pivot-pin.

10. A cuff-link or button having a bifurcated shank, a pivot-pin of rectangular cross-section extending between the bifurcations of the shank, a hollow head formed with circular openings in its sides through which the pivot-pin projects to rockably mount the head on the shank, a locking element slideable within the head and having a central slot engageable with the flat sides of the pivot-pin to lock the head from rocking thereon, said locking element having one or more circular openings communicating with the end of the slot and adapted to be shifted into position to enclose the pivot-pin when the locking element is slid in one direction or the other whereby to unlock the head and allow it to rock on the pivot-pin, and resilient means for normally maintaining said locking element with its slot in engagement with the flat sides of the pivot-pin.

11. A cuff-link or button having a bifurcated shank, a pivot-pin extending between the bifurcations of the shank and formed with flat faces on its sides, a tubular head having circular openings in its sides for pivotally mounting the head to rock on the pivot-pin between the bifurcations of the shank, a locking element of tubular form slideable in the head and formed with slots in its sides with flanges projecting inwardly therefrom for engagement with flat sides of the pivot-pin to restrain the head from rocking on the pivot-pin, circular openings at the ends of the slots communicating therewith to adapt them to be shifted into position enclosing the pivot-pin to permit the head to rock thereon, plungers slideable in the locking element, and springs in the locking element for sliding the plungers to engage them with the ends of the flanges at the sides of its slots to hold said plunger from engagement with the pivot-pin, said springs being yieldable to permit the locking element to be slid in either direction to release the flanges from the flat faces on the pivot-pin.

CARL I. OSTERBERG.
